(57) CLAIM

The ornamental design for a hair stylizing apparatus, as shown and described.

DESCRIPTION

FIG. 1 is a perspective view of the hair stylizing apparatus of the present invention;

FIG. 2 is a first side elevation view of the hair stylizing apparatus;

FIG. 3 is a second side elevation view of the hair stylizing apparatus;

FIG. 4 is a front axial view of the hair stylizing apparatus;

FIG. 5 is a rear axial view of the hair stylizing apparatus;

FIG. 6 is a top plan view of the hair stylizing apparatus; and,

FIG. 7 is a bottom plan view of the hair stylizing apparatus.

Any portions of the figures shown in broken lines are for illustrative purposes only and form no part of the claimed design.
